Primary Examiner — Dana K Weiland*(74) Attorney, Agent, or Firm* — Polson Intellectual Property Law, PC; Margaret Polson**CLAIM**

The ornamental design for a body of a smart watch, as shown and described.

DESCRIPTION

FIG. 1 is a top, right side isometric view of our new design for a body of a smart watch.

FIG. 2 is a top side plan view of FIG. 1.

FIG. 3 is a right side elevation view of FIG. 1.

FIG. 4 is a left side elevation view of FIG. 1.

FIG. 5 is a front side elevation view of FIG. 1

FIG. 6 is a back side elevation view of FIG. 1; and,

FIG. 7 is a bottom plan view of FIG. 1.

The features shown in broken lines in the drawing depict portions of the body of a smart watch that form no part of the claimed design.
